UNITED STATES PATENT OFFICE.

CHARLES C. SCHULER, OF WINONA, MINNESOTA.

DESIGN FOR A CANDY BOX OR SIMILAR CONTAINER.

Application filed April 27, 1925. Serial No. 13,235. Term of patent 7 years.

To all whom it may concern:

Be it known that I, CHARLES C. SCHULER, a citizen of the United States, residing at Winona, in the county of Winona and State of Minnesota, have invented a new, original, and ornamental Design for a Candy Box or Similar Container, of which the following is a specification, reference being had to the accompanying drawing, forming part thereof.

Referring to the drawings:—

Fig. 1 is a perspective view of the box; and Fig. 2 is a vertical cross section of the same.

What I claim is:—

The ornamental design for a candy box or similar container, as shown.

CHARLES C. SCHULER.
